UNITED STATES PATENT OFFICE.

EDWARD MOUNTAIN, OF GREENVILLE, MAINE, ASSIGNOR OF ONE-HALF TO GEORGE MOUNTAIN, JR., OF GREENVILLE, MAINE.

BUOYANT RAFT.

Application filed May 24, 1924. Serial No. 715,569.

To all whom it may concern:

Be it known that I, EDWARD MOUNTAIN, a citizen of the United States, and resident of Greenville, in the county of Piscataquis 5 and State of Maine, have invented certain new and useful Improvements in Buoyant Rafts, of which the following is a specification.

As is well known it is common practice 10 in logging operations to float the logs considerable distances down rivers or even to tow the same on lakes or other large bodies of water. Many kinds of wood are light enough to float with only a part thereof submerged but others will sink almost wholly beneath the surface of the water. It has been usual to load these on barges or scows for water transportation. Obviously this 15 practice consumes much time and labor.

20 My invention relates to the construction of a buoyant raft formed of relatively light logs which will float readily, to which the heavy logs that it is desired to transport may be readily fastened, thus enabling 25 them to be transported as desired.

An object of the invention is to provide 30 such a raft that will be easy to construct and efficient in operation, wherein the structure of the raft is such that it can be repeatedly used.

Another object is the provision of means 35 for attaching the logs to be towed in such manner that they may be readily and easily detached from the raft.

Other objects of the invention will be apparent 40 from the following detailed description and the appended claims.

In the drawings:

Figure 1 is a top plan view of the loaded 45 raft.

Figure 2 is a detail showing the manner 50 of attachment of the individual logs to be transported.

Figure 3 is a side elevation of the unloaded 55 raft.

Figure 4 is a cross section thereof.

Figure 5 is a side elevation of the loaded 60 raft.

The raft is composed of two side members 55 comprising a plurality of longitudinally extending logs or timbers 1. As illustrated there are three vertical rows of three logs each, but the number of rows or the number of logs in each row may be varied 65 without departing from the spirit of the in-

vention. Each horizontal row is separated from the adjacent row by a short log or timber 2, these being placed at a plurality of points lengthwise of the logs 1. At the front the log 2 is replaced by a log 3 which 60 extends from one side of the raft to the other. About the middle of the raft and at the rear end, an additional log 4 is placed on top of the upper timbers 1 and extends from one side of the raft to the other. The 65 width of the raft is determined by the length of the logs 3 and 4. Each vertical tier of logs 1 is connected together and to the cross pieces 2, 3 and 4 respectively, by bolts 5 as clearly illustrated. Near its 70 middle the front cross piece 3 is provided with an eye, hook, or equivalent member 6 by which the raft is connected to the tow or to adjacent rafts.

At suitable intervals the top pieces 1 of 75 each side are provided with eyes 7 through which pass chains 8. These chains are attached to the inner row of logs in the drawings, but obviously can be attached to either of the other rows or to a plurality of rows if 80 desired. The ends of the chains may be secured in any manner. As shown in the detail drawing in Figure 2, the ends of the chains may terminate in hook members 9 which will pass through the eyes 7, but 85 which when hooked into an adjacent link of the chain will prevent disengagement thereof.

Carried on each chain is a plurality of ring dogs 10 as shown in Figure 2 which 90 have an eye or ring through which the chain passes and which have freely slidably thereon a hook or dog member 11 that may be driven into the logs A to be towed. The logs are arranged in the raft as shown in 95 Figures 1 and 5, the chains 8 being relatively taut and the ring dogs being fastened to the front ends of the logs. Being supported at the front end only, these logs will assume a position inclined towards the 100 rear, and the second chain 8 will be positioned so that the second series of logs A will overlap the first series considerably. Similarly the third series overlaps the second, and so on. This arrangement permits the assembly of a large number of logs 105 in a compact manner with great saving of space and with no interference.

Other eyes 12 are attached to the top logs 110 of one of the tiers, and chains 13 which pass

through these eyes and are held in position similarly to the chains 8 pass down from one top log 1, underneath the front ends of the series of logs A and up on the top log 5 1 on the opposite side of the raft. This furnishes an additional support for the logs being towed and prevents accidental disengagement of the logs from the ring dogs. While only one of these chains 13 is illustrated, it is to be understood that they may 10 be used in connection with each series of logs A if desired.

It is evident that I have provided a simple and efficient means for constructing 15 a raft to which the logs to be towed may be attached quickly and removed with equal ease. The raft may be repeatedly used as there is no necessity for dismantling it when it is unloaded. A large number of 20 logs may be attached to a single raft in compact form, and any desired number of rafts may be connected. Obviously changes in the forms and dimensions may be made 25 and the precise construction changed in many details without departing from the spirit of the invention. It is, therefore, to be understood that the invention is to be regarded as limited only by the scope of the appended claims.

30 I claim as my invention:

1. A buoyant raft comprising side members each composed of a plurality of rows and tiers of logs, horizontal spacing members intermediate each pair of said rows, 35 transverse members extending from one side of the raft to the other and connecting said side members, means for fastening said members together, transverse chains carried by the said members, and devices carried by said 40 chains for engaging the logs to be supported by said raft.

2. A buoyant raft comprising side members each composed of a plurality of verti-

cally spaced rows of logs, spacing members between said rows, transverse members connecting the side members, means for fastening all of said members together at engaging points, transverse chains carried by the side members, and devices carried by said chains for engaging the logs to be supported 45 by the raft.

3. A buoyant raft comprising side members each composed of a plurality of vertically spaced rows of logs, means connecting and spacing said side members, transverse 50 chains carried by said side members, and devices carried by said chains for engaging the logs to be supported by the raft.

4. A buoyant raft comprising side members each composed of a plurality of vertically spaced rows of logs, means connecting and spacing said side members, transverse chains carried by said side members, devices carried by said chains for engaging the logs 55 to be supported by the raft, and other chains 60 attached to the side members and passing under said logs.

5. A buoyant raft comprising side members, means connecting said side members, transverse chains carried by the side members, dogs carried by said chains and adapted to engage the logs to be supported by the raft, and other transverse chains attached to the side members and passing under the 70 front ends of said logs.

6. A buoyant raft comprising side members, means connecting and spacing said side members, transverse chains carried by said side members, and means carried by said chains for engaging the front ends of the 75 logs to be supported by said raft whereby a plurality of series of said logs may be supported in overlapping relation.

In testimony whereof, I have hereunto subscribed my name.

EDWARD MOUNTAIN.
